R. C. RUSSELL

CARD INDEX

Filed Nov. 14, 1922

By *Seymour & Bright*
Attorneys

UNITED STATES PATENT OFFICE.

ROBERT C. RUSSELL, OF PITTSBURGH, PENNSYLVANIA.

CARD INDEX.

Application filed November 14, 1922. Serial No. 600,929.

To all whom it may concern:

Be it known that I, ROBERT C. RUSSELL, a citizen of the United States, and a resident of Pittsburgh, in the county of Allegheny and State of Pennsylvania, have invented certain new and useful Improvements in Card Indexes; and I do hereby declare the following to be a full, clear, and exact description of the invention, such as will enable others skilled in the art to which it appertains to make and use the same.

This invention relates to improvements in card indexes of the visible type,—objects of the invention being to provide a simple one-piece construction of combined card and support which may be made to interlock or intermesh with like combined devices in a holder and prevent removal of such combined devices collectively, but to permit them to be removed or inserted singly,—the construction being such that the combined devices may be moved singly or collectively in the holder and be guided in ways afforded by the latter without necessity for providing said combined devices with tongues projecting laterally beyond the side edges of the cards or their supports, thus permitting the use of a narrow holder for the combined devices, and to so construct said combined devices that they may when assembled overlie the guide-flanges of a holder and thus be made a width approximately equal to that of the holder.

With these and other objects in view, the invention consists in certain novel features of construction as hereinafter set forth and pointed out in the claims.

In the accompanying drawings,—

Figure 1 is a face view illustrating a card index embodying my improvements.

Figure 2 is a view of a blank from which the combined card and card support may be made.

Figure 3 is a perspective view showing one of the combined devices.

Figure 4 is a similar view showing the back of one of the combined devices.

Figure 5 is a view in section on the line 5—5 of Figure 4.

Figure 6 is a view in section on the line 6—6 of Figure 4.

Figure 7 is a view in section on the line 7—7 of Figure 4, and

Figure 8 is a view of a modification.

In Figure 1 of the drawing I have shown the holder 1 for cards, said holder being

preferably made of sheet metal and provided at its side edges with flanges 2 forming guideways for tongues integral with card supports as hereinafter explained.

60

The holder 1 receives a plurality of overlying cards and their supports and each such combined device may be made of cardboard or similar material.

In the combined device represented by the blank, Figure 2, the portion 3 constitutes an index card while the portion 4 provides a support for said card and means for mounting the same on a holder 1. The blank shown in Figure 2 is provided with score or folding lines 4—5 and centrally between the side edges of the device the strip 6 formed between the lines 4 and 5 is cut to provide a tongue 7. The upper portion of the blank shown in Figure 2 is slotted as at 8—8 to form tongues 9—9 and these tongues are made short so as to terminate inwardly of the side edges of the remaining portion of the device including the card member 3. The upper portion of the blank will be folded on the line 5 and cemented or otherwise secured to the back of part 6 and the score or folding line 4 will provide a hinge connection between the card member 3 and its support 4. The tongue 7 is so cut from the material that when the device shall have been folded in the manner above explained, a slot or opening 10 will be formed and when the device shall have been folded, the portion of the support member which carries the tongues 9 will be disposed behind the card member 3 and may be readily inserted in the guide-ways formed by the flanges 2 of the holder. It will be observed that when a combined device 3—4 is mounted on the holder with the tongues entering the guideways thereof, the major portion of the sides of both the card and its support will overlie the flanges 2 of the holder and thus the width of the combined device may be approximately equal to the width of the holder and a narrow holder may therefore be employed. When the combined device shall have been assembled, the tongue 7 of one will pass through the slot or opening 10 of another and the several combined devices will therefore be interlocked and may be moved either singly or collectively to expose the index card which the user may desire to examine or make an entry upon.

90

The construction shown in Figure 8 is similar to that shown in the other views, ex-

cept that the tongue 7 and slot 10 are omitted.

Having fully described my invention what I claim as new and desire to secure by Letters Patent, is:

1. In a card index, the combination with a holder having guide-ways, of combined devices each comprising in a single piece, a card member and a support member adapted 10 to overlie the guide-ways of the holder and each combined device also comprising tongues terminating inwardly of the side edges of said device and adapted to enter the guide-ways of the holder.
- 15 2. In a card index, the combination with a holder having guide-ways, of combined devices each comprising in a single piece, an index card member and a support member therefor having hinge connection with the 20 card member, said support member having tongues terminating inwardly of the side edges of the device and adapted to enter the guide-ways of the holder.
- 25 3. In a card index, the combination with a holder having side flanges forming guide-

ways, of a plurality of combined index devices, each comprising a card member and a support member, the card member having hinge connection with the support member, each combined device having a central 30 tongue and a slot adjacent thereto and laterally projecting tongues terminating inwardly of the side edges of the device, said combined device being foldable on two lines to dispose the first mentioned 35 tongue upwardly and the portion of the support having the lateral tongues behind the card member, said lateral tongue entering the guide-ways of the holder and the side portions of the card and its support disposed upon the side flanges of the holder which forms said guide-ways.

In testimony whereof, I have signed this specification in the presence of two subscribing witnesses.

ROBERT C. RUSSELL.

Witnesses:
